UNITED STATES PATENT OFFICE.

LOUIS COUNARD, OF BRUSSELS, WISCONSIN, ASSIGNOR OF ONE-THIRD TO FELIX J. COUNARD AND ONE-THIRD TO JOHN J. NEVILLE, BOTH OF GREEN BAY, WISCONSIN.

SECURING AND LOCKING SLIDING DOORS.

Application filed February 4, 1922. Serial No. 534,117.

To all whom it may concern:

Be it known that I, Louis COUNARD, a citizen of the United States, and resident of Brussels, in the county of Door and State of Wisconsin, have invented new and useful Improvements in Securing and Locking Sliding Doors, of which the following is a description, reference being had to the accompanying drawings, which are a part of this specification.

This invention relates to improvements in securing and locking sliding doors, particularly sliding doors supported on the outside of the door opening.

Among other objects, the invention is intended to provide novel and improved means for securing and locking doors of this type against the outward displacement of the lower portion thereof.

The invention consists in the novel combinations, constructions and arrangements, hereinafter described or claimed, for carrying out the above stated objects and such other objects as will hereinafter appear.

The character of the invention may be best understood by referring to an illustrative construction embodying the invention and shown in the accompanying drawing.

In said drawing:

Fig. 1 is an elevation of a pair of sliding doors supported to slide on the outside of the door opening.

Fig. 2 is a section of a detail taken along the line 2—2 of Fig. 1.

Fig. 3 is a detail section taken along the line 3—3 of Fig. 1.

Fig. 4 is an elevation showing the locking device.

Fig. 5 is a section taken along the line 5—5 of Fig. 4, showing an arrangement for locking the doors.

Fig. 6 is a detail section taken along the line 6—6 of Fig. 1.

In the drawing, 10 and 11 represent a pair of sliding doors, such as barn doors supported by suitable devices to slide along a track on the exterior of the door frame 13. Ordinarily, in barn doors of this type the lower portions thereof are free to swing outwardly from the door opening in the event pressure is exerted upon them, thus insecurely covering the door opening.

In the illustrative construction, each door is provided on the lower portion thereof with a hook member arranged so that the

extremity thereof will engage a staple 15, or the like, when the door is closed. The staples 15 are preferably secured to the wall adjacent the door opening and are designed to prevent the outward swinging of the door or doors when they are in closed position.

The front edges 16 of the doors are recessed at 17 to permit the member 18 to project beyond the doors when closed. The member 18 is provided with an angularly projecting lug 19 and is preferably supported by the ordinary bar 20 which extends across the door opening inside the doors. This bar is supported by the usual hooks 21 and may be removed in the usual manner when it is desired to pass through the door.

A latch 22 pivoted at 23 to one of the doors is arranged to swing behind the lug 19 when the doors are closed to assist in preventing the outward swinging of the doors. This latch may be constructed to serve as a lock, if desired, by providing an angularly projecting lug 24 thereon arranged to fall behind the hook 25 secured to the other door. This hook preferably is merely an extension of a handle 26 secured to the door and by means of which the door may be moved.

If desired the lug 24 may be perforated and the hook 25 provided with a lug 27 having an opening therein registering with the opening in the lug 24. A lock, such as a padlock, may be passed through the registering openings in order to lock the doors against unauthorized opening.

It is obvious that the construction herein may be variously modified and it is not essential that all features be used conjointly. Certain constructions and arrangements may be advantageously employed in various combinations and sub-combinations.

I claim:

1. The combination with a pair of sliding doors supported to slide across the door opening, a latch pivoted to one of said doors and a keeper member supported independently of said doors adjacent the abutting ends of said doors and arranged to receive said latch, a hook on the other door arranged to receive said latch and a lug on said latch for preventing the withdrawal thereof from said hook.

2. The combination with a pair of sliding doors supported to slide across the door

opening, a latch pivoted to one of said doors, and having an angularly projecting lug, a keeper member having an angularly disposed extremity supported by a bar across 5 the inside of the door frame so as to project beyond said latch, a hook member on the other door arranged to receive said latch to prevent the opening of the doors, said latch arranged to fall behind the angular 10 extremity of said keeper member for the purpose described.

3. The combination with a pair of sliding doors supported to slide across the door opening, a latch pivoted to one of said doors, and having an angularly projecting, perforated lug, a keeper member having an angularly disposed extremity supported by a bar across the inside of the door frame so as to project beyond said latch, a hook member 15 on the door arranged to receive said latch to prevent the opening of the doors, said hook provided with a perforated lug 20

adapted to register with the opening in the lug on said latch so as to receive a lock.

4. The combination with a pair of sliding 25 doors supported to slide across the door opening, a latch pivoted to one of said doors, and having an angularly projecting, perforated lug, a keeper member having an angularly disposed extremity supported by a 30 bar across the inside of the door frame so as to project beyond said latch, a hook member on the door arranged to receive said latch to prevent the opening of the doors, said hook provided with a perforated lug adapt- 35 ed to register with the opening in the lug on said latch so as to receive a lock, said latch arranged to fall behind the angular extremity of said keeper member to prevent said doors from swinging away from the 40 door opening.

In testimony whereof, I affix my signature.

LOUIS COUNARD.
